US00D486158S

(12) **United States Design Patent** (10) **Patent No.:** **US D486,158 S**
Lei et al. (45) **Date of Patent:** **** Feb. 3, 2004**

(54) **IMPELLER**

(75) Inventors: **Tsung-Yu Lei**, Taipei (TW);
Kuo-Cheng Lin, Taoyuan (TW);
Wen-Shi Huang, Taoyuan (TW)

(73) Assignee: **Delta Electronics Inc.**, Hsien (TW)

(**) Term: **14 Years**

(21) Appl. No.: **29/173,075**

(22) Filed: **Dec. 23, 2002**

(51) LOC (7) Cl. **15-02**

(52) U.S. Cl. **D15/7**

(58) Field of Search .... **D15/7-9; 416/185, 416/188, 198 R, 198 A, 199.1, 186 R, 193 R**
